UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WASHER-PLACING APPARATUS.

1,422,159.

Specification of Letters Patent.

Patented July 11, 1922.

Application filed December 16, 1916, Serial No. 137,368. Renewed December 17, 1920. Serial No. 431,500.

To all whom it may concern:

Be it known that I, ERASTUS E. WINKLEY, a citizen of the United States, residing at Lynn, in the county of Essex and State of Massachusetts, have invented certain new and useful Improvements in Washer-Placing Apparatus; and I do hereby declare the following to be a full, clear, and exact description of the invention, such as will enable others skilled in the art to which it appertains to make and use the same.

The present invention relates to an improvement in blank-handling apparatus, and more particularly to an improvement in washer-placing apparatus especially adapted for use in placing the nail-holding washers in the molds in which rubber heels or like articles of manufacture are molded.

Those skilled in the art will recognize from the following description that certain features of the invention in their broader aspect are not limited to use in a machine for placing washers in rubber heel molds, but may be employed in apparatus for transferring blanks of other characteristics and for other uses.

The chief object of the invention is to produce a washer-placing apparatus of such construction that the operation of depositing the nail-holding washers on the washer-supporting pins in rubber heel molds may be rapidly, positively and accurately performed. These washers are embedded in the molded heels and thereby serve as supports for the nails by which the heels are secured to the shoes. To the accomplishment of this object and such other objects as shall hereinafter appear, the invention consists of the improved washer-placing apparatus described in the following specification and particularly pointed out in the appended claims.

The preferred embodiment of the invention is illustrated in the accompanying drawings, in which Figures 1, 2 and 3 are, respectively, a plan, a side elevation, and an end elevation of the washer-placing apparatus; Fig. 4 is an enlarged sectional view of one of the washer-placing units shown in the act of picking a washer from one of the supply stacks; and Fig. 5 is a similar view, partly in elevation, showing the unit in the act of depositing a washer on one of the washer-supporting pins in a heel mold.

The washer-placing apparatus illustrated in the drawings comprises three groups of washer-placing units, each group containing five units which correspond to the five nail-supporting pins in the heel molds. The groups may be of any convenient number and the number of units in each group will, of course, depend upon the number of nails used in securing the heel to the shoe. The washer-placing units, which are generally indicated at 10, are mounted for operation in a supporting frame consisting of an upper frame 11 and a lower frame 12. The lower frame 12 is secured to two elongated sleeves 14 and 15 which are adapted to slide upon vertically disposed guide posts 16 and 17 secured in a base 18, upon which are mounted the heel molds 20 and the stacks 21 of reserve washers. The upper frame 11 is provided with bosses 22 through which are bored holes to enable the upper frame to slide upon the sleeves 14 and 15 toward and from the lower frame. The frames are manipulated by means of handles 24. The guide posts are four in number, the two guide posts 16 being disposed in alignment with the reserve stacks 21 and the two guide posts 17 being disposed in alignment with the heel molds 20. These guide posts serve to guide the frames when the washers are picked from the reserve stacks and to guide them in depositing the washers on the supporting pins of the heel molds so that the picking and depositing operations may be rapidly and accurately performed. In the heel molds 20 are arranged in the usual manner the washer-supporting pins 26. Each pin 26 is provided with a teat 27; and the shoulder 28 formed at the junction of the teat and the lower part of the pin is at such distance from the bottom of the mold that, when a washer has been properly placed thereon and the heel has been molded, the washer will be embedded in the heel on substantially the median plane parallel with the top and bottom faces of the heel. The stacks 21 of reserve washers are held in position on vertically-disposed pins 29 which correspond in arrangement with the washer-supporting pins 26 in the heel mold. It is to be observed that the guide posts 16 are in the same relative position with respect to the pins 29 that the guide posts 17 are in with respect to the pins 26. Each washer

30 is provided at its center with a round nail hole slightly larger than the pins 29 and the teats 27. The washers may be flat or concaved; and herein resides one of the 5 advantages of the present invention, that it is equally well adapted to handle expeditiously either flat or concaved washers.

Each washer-placing unit comprises a washer picking sleeve 32 and a washer ejecting or depositing plunger 33. The washer picking sleeves 32 are held in position and guided in their picking operations in holes in the lower frame 12 and in a plate 35, which is held in fixed relation with the lower 10 frame 12 by means of bolts and collars 36. The lower end or head 38 of each washer picking sleeve is counter-sunk at 39, as shown in Figs. 4 and 5, so that only one washer may be grasped at a time. As shown in said 15 figures of the drawings the diameter of the lower open end of the picker is greater than the diameter of the washer to be transferred, although it will be observed the inward taper of the washer gripping wall is such that at 20 a point above the open end a washer will be firmly held by frictional engagement with the edge thereof. The tapering washer-engaging walls provide a picker construction which, when the picker is forced down over 25 the stack, leaves all the washers below the uppermost one disengaged and insures the transfer of a single washer at a time from each stack. When the apparatus is neither 30 in the act of picking washers nor in the act 35 of depositing them, springs 41, encircling the reduced shanks 42 of the picking sleeves, serve to keep the collars 43, secured to the upper ends of the shanks 42, against the top of the lower frame 12, and thereby hold the 40 picking sleeves in normal position. Each washer depositing plunger 33 slides freely in a washer picking sleeve and is secured at its upper end to the under side of the upper frame 11. The lower ends of the plungers 45 are bored at 44 to permit the plungers to pass freely over the pins 29 in the picking operations, and over the teats 27 in the depositing operation. The lower extremities of the plungers may be slightly counter-sunk 50 to correspond to the convexity of the washers. Springs 45, embracing the upper ends of the plungers and interposed between the collars 43 and the upperframe 11, serve to normally maintain the upper frame apart 55 from the lower frame so that at all times, except during the washer depositing operation, the lower ends of the plungers will be well within the lower ends of the picking sleeves so as not to interfere with the picking operation or to prematurely discharge 60 the washers from the sleeves.

In performing the operation of simultaneously placing washers on all the washer-supporting pins in the series of heel molds, 65 the washer-placing apparatus is first low-

ered over the stacks of reserve washers, each washer placing unit being guided over its corresponding stack of washers because of the fixed relation between the units and the sleeves 14 and 15, and because of the corresponding fixed relation between the stacks and the guide posts 16. When the apparatus has been lowered over the supply stacks 70 the weight of the whole apparatus is such as to cause the counter-sunk ends 39 of the 75 picking sleeves to fit tightly over the top washers. The uppermost washer is thus, by reason of the described construction of the picker device, gripped exteriorly by lateral pressure on its edge when the frame is 80 dropped down over the guide posts 16 and the pickers are permitted to engage with the reserve stacks of washers. The weight of the lower frame is communicated to the 85 picking sleeves through the springs 41, which are somewhat compressed during the picking operation, as shown in Figs. 2 and 4. The weight of the upper frame is communicated to the picking sleeves through the springs 45, which are of such strength that 90 they are not compressed by the weight of the upper frame during the picking operation, but hold the upper frame at its normal distance from the lower frame and thereby hold the lower ends of the ejecting plungers 95 33 away from the top washers, as shown in Fig. 4. In depositing the washers on the supporting pins in the heel molds, the apparatus is guided into depositing position 100 by the guide posts 17. When the washer-placing units have been thus properly positioned over their corresponding washer-supporting pins, the operator grasps the handles 24 firmly, drawing each set of handles 105 toward each other. This action first moves the lower frame up against the collars 43 because at this time the frame 12 is in the position shown in Fig. 2, except that the apparatus is over the heel molds and not over the reserve stacks. When the lower frame 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 of operation of the washer-placing apparatus of the present invention that washers are rapidly, positively and accurately positioned on the washer-supporting pins in 5 molds adapted for the manufacture of rubber heels.

It is to be observed that the stacks of reserve washers are located conveniently near the heel molds, so that it is merely necessary for the operator to take the washer-placing apparatus from its normal position over the stacks of reserve washers and guide it into operative position over the heel molds without other effort than the movement of 10 his arms. It is not necessary of course to the accomplishment of the object of the invention that the stacks of reserve washers and the heel molds be mounted upon the same base. The purposes of the invention 15 will be accomplished so long as the guide posts 16 bear the same relative position to the pins 29 as the guide posts 17 bear to the pins 26 in the heel molds. The construction illustrated in the drawings, however, provides a unitary and compact apparatus 20 which greatly facilitates the operator in the operation of molding rubber heels and the like.

It will readily be understood by those 30 skilled in the art that the novel mode of engaging and transferring blanks singly hereinbefore described is not limited to the handling of blanks of disc form, such as the washers specifically described, but that the 35 principle of a lateral, or edge pressure, may be employed in gripping blanks designed for various uses and which have different forms consonant with the use for which they are intended.

40 Having thus described the preferred embodiment of the invention, it being understood that the invention is not limited to the construction shown and described, what is claimed is:—

45 1. A washer-placing apparatus, having in combination, heel molds and washer-supporting pins fixed therein, guide posts in fixed relation with said pins, pins for holding stacks of reserve washers arranged correspondingly to the arrangement of the washer-supporting pins, guide posts fixed in the same relation with the reserve stack pins as the formed guide posts bear to the washer-supporting pins, and a member guided in its 50 operation by the guide posts for transferring the washers from the reserve stacks to the washer-supporting pins.

60 2. A washer-placing apparatus, having in combination, heel molds provided with washer supporting-pins, pins for holding stacks of reserve washers having the same arrangement as the washer-supporting pins, washer-placing units arranged correspondingly to the two sets of pins for picking a 65 washer from each reserve stack and for de-

positing the washers on the washer-supporting pins, and means for supporting and operating the washer-placing units.

3. A washer-placing apparatus, having in combination, heel molds provided with 70 washer-supporting pins, pins for supporting stacks of reserve washers having the same arrangement as the washer-supporting pins, two sets of guide posts, one set in fixed relation with the washer-supporting pins, and the other set in corresponding fixed relation with the reserve stack holding pins, washer-placing units arranged correspondingly to the two sets of pins for picking the washers from the reserve stacks and transferring them to the washer-supporting pins, and means guided by the guide posts for supporting and operating the washer-placing units.

4. A washer-placing apparatus, having in 85 combination, heel molds provided with washer-supporting pins, pins for holding stacks of reserve washers having the same arrangement as the washer-supporting pins, washer-placing units having sleeves 90 arranged correspondingly to the two sets of pins for picking the top washers from the reserve stacks, a frame for supporting the units, guide posts in fixed relation with the reserve stack pins for guiding the frame 95 during the picking operation, said washer-placing units also having plungers for depositing the washers on the washer-supporting pins, and guide posts fixed in the same relation to the washer-supporting pins as 100 the formed guide posts bear to the reserve stack pins for guiding the frame during the depositing operation.

5. A washer-placing apparatus, having in combination, heel molds provided with 105 washer-supporting pins, pins for holding stacks of reserve washers, and a device for transferring washers from the reserve stacks to the pins comprising means for picking a washer from each stack simultaneously, and 110 means for depositing the washers so picked simultaneously on the washer-supporting pins in the heel molds.

6. A washer-placing apparatus, having in combination, heel molds provided with 115 washer-supporting pins, guide posts in fixed relation with said pins, pins for supporting stacks of reserve washers, guide posts in the same fixed relation with respect to the reserve stack pins as the first guide posts are 120 in with respect to the washer-supporting pins, a frame adapted to be guided in its operation by the guide posts, a second frame movable toward and from the first frame, washer-placing units arranged correspondingly to the two sets of pins consisting of picking sleeves loosely supported in the first frame, and depositing plungers rigidly secured to the second frame.

7. A device for transferring stacks of 130

- washers from one place to another comprising a series of washer-picking sleeves arranged in a predetermined relation correspondingly to the stacks of washers to be transferred, and designed to simultaneously remove a plurality of washers from the stacks, plungers mounted in the sleeves for discharging the washers therefrom, and means for supporting and operating the sleeves and the plungers.
8. A device for transferring stacks of washers from one place to another comprising a series of washer-transferring units arranged in a predetermined relation correspondingly to the stacks to be transferred, each unit consisting of a washer-picking sleeve and a washer-discharging plunger, a frame for loosely supporting the sleeves, a second frame for rigidly supporting the plungers, and means for normally holding the frames apart.
9. A washer-placing apparatus comprising a sleeve having a counter-sunk tapered end adapted to engage and hold a washer, a plunger sliding within the sleeve, and means for actuating the plunger to eject a washer from the counter-sunk end of the sleeve.
10. A washer-placing apparatus comprising a pin for holding a stack of reserve washers, a washer-carrying sleeve having a counter-sunk end adapted to engage the top washer of the stack, and a plunger for ejecting the washer from the sleeve having a longitudinal bore adapted to receive the pin when the sleeve is positioned upon the stack of washers.
11. A washer-placing apparatus comprising a heel mold having a washer-supporting pin fixed therein, a sleeve adapted to receive and hold a washer in the lower end, a plunger sliding within the sleeve, and means for actuating the plunger to cause the latter to forcibly deposit the washer upon the supporting pin in the heel mold.
12. A device for transferring stacks of blanks from one place to another comprising a blank picker having a blank engaging end constructed, proportioned and arranged to grip exteriorly and transfer the end-most blank only of the stack.
13. A device for transferring stacks of blanks from one place to another comprising a blank picker adapted to be forced down over the upper end of the stack and constructed to grip the uppermost blank only by its edge for transferral to another location.
14. A device for transferring stacks of blanks from one place to another comprising a blank picker open at its blank engaging end, the opposite inner walls of which taper from said open end inwardly, adapted to be placed over the stack and seize the end-most blank by frictional engagement with the edge thereof.
15. A device for transferring stacks of blanks from one place to another comprising a blank picker having a blank engaging portion constructed to exert a lateral gripping pressure on the uppermost blank of the stack through an edge engagement therewith when forced into engagement with said blank through a movement in the direction of the length of the stack.
16. A device for transferring stacks of blanks from one place to another comprising a blank picker having an open lower end adapted to be forced down over the upper end of the stack to a position for gripping the uppermost blank by pressure against opposed edge portions thereof, said blank gripping portion of said device having a wider opening at its lower end than the dimension of the blanks to be gripped but tapering to a dimension capable of gripping opposed edge portions of said uppermost blank, whereby all but the uppermost blank are left free and a single blank at a time is removed by said device from the stack.
17. A device for transferring stacks of blanks from one place to another comprising means constructed and arranged to grip the edge portion of the endmost blank only of a stack of blanks, in combination with additional means for engaging a blank so gripped and ejecting it from the device.
18. A device for transferring stacks of blanks from one place to another comprising means constructed and arranged to grip the edge portion of the endmost blank only of a stack of blanks, in combination with an ejector carried by said device in a position above the blank, and means for relatively moving the device and ejector to disengage the blank from the device.
19. A device for transferring blanks separately from a stack to a selected point of deposit comprising means constructed to grip the edge portion of the endmost blank only of the stack, in combination with a plunger for forcing the blank out of said gripping means, and means for causing said plunger to function when the blank is at said point of deposit.
20. A device for transferring blanks separately from a stack to a selected point of deposit comprising means constructed to grip the edge portion of the endmost blank only of a stack, in combination with a blank ejector arranged centrally within said gripping device adapted to press upon the face of the blank and release it, and means for causing a relative longitudinal movement between said device and ejector to effect such pressure and disengagement.
21. A device for placing washers upon the washer-supporting pins of a rubber heel mold comprising a stack-pin adapted to

hold a stack of supply washers, and means for transferring the washers of the stack one at a time to mold-pins.

22. A device for placing washers upon the washer-supporting pins of a rubber heel mold comprising a stack-pin adapted to hold a stack of supply washers, and means operating to separate an end washer from the stack and drop it on a mold-pin.

10 23. A device for placing washers upon the washer-supporting pins of a rubber heel mold comprising a series of stack-pins arranged in the same pattern as that of the mold-pins and adapted each to hold a stack 15 of washers, and means for transferring washers one from each stack pin to the corresponding mold-pin.

24. A device for placing washers upon the washer-supporting pins of a rubber heel mold comprising a series of stack-pins arranged in the same pattern as that of the mold-pins and adapted each to hold a stack of washers, and means for transferring washers simultaneously one from each stack pin to the corresponding mold-pin. 25

25. The method of placing washers on the washer-supporting pins of a heel mold which consists in providing stacks of washers on pins arranged in the same pattern as that of the mold-pins, and then 30 transferring end washers, one from each stack, to the mold-pins.

ERASTUS E. WINKLEY.
